TRAVELING-CYLINDER WEB-PRINTING MACHINE.

No. 852,465.

Specification of Letters Patent.

Patented May 7, 1907.

Application filed November 30, 1896. Serial No. 613,928.

To all whom it may concern:

Be it known that I, LOUIS W. SOUTHGATE, a citizen of the United States, residing at Worcester, in the county of Worcester and 5 State of Massachusetts, have invented a new and useful Improvement in Traveling-Cylinder Web-Printing Machines, of which the following is a specification.

The aim of this invention is to improve 10 the traveling cylinder web printing machine.

As such machines are ordinarily constructed, it has been found practical and feasible to make the same wide enough to manipulate a web so that the same will be 15 printed with four of the ordinary newspaper forms abreast. By this arrangement, either a four, six or eight page paper can be produced. But it has not been found feasible to 20 arrange the machine to print on a web wider than four forms, because the cylinders made of the requisite width therefor spring, and prevent a perfect impression.

The especial object of my invention is to 25 so arrange the ordinary traveling cylinder printing press that an additional or supplemental web may be printed therein, if desired, so as to produce a larger paged product.

The especial arrangement that I have invented consists in combining with the ordinary traveling cylinder web perfecting printing machine a third bed and cylinder, and in providing a deflector device so that 30 a web of narrow width can be perfected, and I also provide devices whereby this perfected narrow-width web can be associated 35 with the web perfected by the machine proper. In this way, I can so increase the capacity of the ordinary traveling cylinder 40 machine arranged to print eight pages that in addition a ten or twelve page paper can be printed if desired. I further so arrange the mechanisms that this third cylinder will only be used when it is desired to make the 45 larger paged product, and I so arrange the parts that one driving mechanism will reciprocate the three impression cylinders. Thus, by a very simple combination with the ordinary press, I can greatly increase the 50 use of the traveling cylinder press so that the same will go into printing offices where the traveling cylinder press, as ordinarily

constructed, cannot be used to supply the large-paged paper necessary.

It is a further object of my invention to 55 improve the details and arrangements of a press constructed as before described; and the specific improvements are hereinafter particularly pointed out in the claims at the 60 end of the specification.

Referring to the accompanying three sheets of drawings which show the best form now known to me for carrying out the principle of my invention, Figure 1 is a side elevation of a press constructed according to 65 my invention, Fig. 2 is a partial plan view of a part I term the deflector, Fig. 3 is a perspective view showing the way that the carriages may be connected, Fig. 4 is a sectional elevation of the press, Fig. 5 is a view similar 70 to Fig. 2 with a narrower web used than is shown in Fig. 2, Fig. 6 is a diagram illustrating one form of gearing that I may use to actuate the various feed mechanisms, and Fig. 7 is a partial plan view of the entire ma- 75 chine.

Referring to the drawings and in detail, it will be seen that I have arranged the parts of my press between the usual side-frames, and I will now describe the parts that go to make 80 up the main part of the machine.

A represents the first bed and B the second bed; C the first traveling impression cylinder, and D the second traveling impression cylinder. These impression cylinders C and D 85 are journaled in frames or carriers E which are fitted to slide in guide-ways formed on the side-frames.

The carriers E are connected by a tie or cross-beam F, which extends across the 90 press, and from one carrier to the other as shown in Fig. 4. The under side of this brace F has a groove cut therein so that the same constitutes a yoke. Fitting in this yoke is a square block f, which is carried by a 95 crank-pin f¹ secured in the top of a large, horizontal bevel-gear f², which is mounted upon a shaft stepped in suitable bearings, as is shown. When this large bevel gear f² is revolved, the cylinders will be reciprocated 100 back and forth.

The beds are shown as arranged horizontally, and as one in advance of the other. Any other desired arrangement may be used.

The web w , which is printed by the cylinders C and D is drawn from a web-roll W, which may be mounted in brackets in the side frames in any of the usual ways. From 5 the web-roll W, the web passes first around guides 10 and 11, then through a continuously running feeding-in device which consists of a drum 12 and a series of co-acting tapes. The web then passes back around a 10 looper L, then to a guide 13 carried by the carriers E, down around the first impression cylinder C, then up around a guide 14 carried by said carriers E, around guide-rollers 15 and 16 secured to the side frames, then 15 around a guide-roll 17 secured in said carriers E, down around the second impression cylinder D, then around a guide-roller 18 secured in said carriers E, to a feeding-out looper L¹. From the looper L¹, the web is 20 continuously drawn out by means of a drawing-out device 19, which consists of a continuously running drum and a set of coacting tapes. From this feeding-out device, the web is led between a pair of slitters 20 and 25 21, which cut the web into two portions. One of these portions is then brought under the other by means of turner bars 22 and 23, so that the two half sections of the web will be associated. The two sections of web then 30 pass around rollers 24 and 25, and over a suitable former-folder as 26, around which the same are drawn by the usual pulling-rollers 27, 27. The guide-roll 15, previously referred to may be made adjustable for the 35 purpose of obtaining register.

Suitable inking-rollers G, G are arranged at each side of each of the impression cylinders C and D, and fountains H, H are provided so that the forms will be properly inked. By this arrangement it will be seen 40 that a web can be perfected, and if the machine is made four forms wide, it will be seen that either a four, six or eight page paper can be produced, depending upon the width of the web and the number of forms used.

I represents a third stationary bed, which is secured between the main frames, preferably in the same horizontal plane as the bed B, and to the rear thereof.

J represents a third impression cylinder which is mounted in carriers E¹ E¹, which are fitted in grooves on the side-frames, which grooves preferably are extensions of the grooves in which the carriers E E are operated.

Arranged in the carriers E¹, E¹ at each side of the impression cylinder J are inking rollers G¹, G¹ which coat with ink-fountains H¹, H¹. The carriers E, E and E¹, E¹ are arranged to 60 abut together, and suitable bosses E² are provided on the abutting ends of each carrier, whereby, by securing bolts E³ in said abutting studs, the carriers E¹ become practically extensions of the carriers E, and will 65 reciprocate therewith. By disconnecting

the bolts E³ and leaving the carriers E¹ in their extreme right-hand position, the cylinder J may be disconnected from operation. This is a very advantageous construction, as it does not increase or complicate the driving mechanism, and provides a simple and efficient means whereby the third cylinder can be thrown into or out of operation as desired. 70

The web w^1 for the third cylinder J may be drawn from a web-roll W¹ which may be mounted in brackets secured to the side-frames, as shown in Fig. 1. From the web-roll W¹, the supplemental web w^1 is drawn by means of the continuously running feeding-in device, which may consist of a roller 29 and a 80 set of coacting tapes. From the feeding-in device, the web w^1 is passed around a looper L², and is then carried back around a roller 30 journaled in the side-frames, and then is carried forward to a guide or roller 31 journaled in the carriers E¹, E¹. The web is then passed under the impression cylinder J, up around a roller 32 also journaled in said carriers E¹, E¹. From the roller or guide 32, the web passes to a part I term the deflector device. 85

One way in which the deflector device may be arranged is to provide two parallel turner-bars as 33 and 34, and a roller 35, which may be secured in brackets projecting inwardly 95 from one of the side-frames, and which roller 35 I term a parallel roller as the same is parallel to the movement of the web through the machine.

The web w^1 passes first up over the angle-bar 33, then down over the parallel roller 35, then up over the angle-bar 34. By this passage of the web, it will be seen that its first printed side will not come in contact with any part of the deflector device. The web w^1 is then led back again around the roller 32, down under the impression cylinder J, and up around a guide-roller 36 journaled in the carriers E¹, E¹. The web w^1 is then led back around the looper L², and from the looper L² is carried to a continuously running feeding-out device 37, which consists of a continuously rotating drum and a set of coacting tapes. From this continuously running feeding-out device, the supplemental or narrow-width web w^1 is associated with the section or sections of the main web, and passes up over the rollers 24 and 25, down over the former 26, and thus inside of the folded product. 115

By leading or associating the supplemental web inside of the main web it will be noted that the product will be folded directly, whether a ten or twelve-paged product is made. That is to say, in making a ten-paged paper, it is necessary to fold the sheet, which consists of two pages only, inside of the other sections, and by leading the supplemental web in the manner indicated, this action always takes place. 125

It will be noticed that the web w^1 is looped 130

in opposite directions around the looper L^2 . This is a very advantageous construction, as, by this arrangement, I use but one looper for the web.

5 If the machine is organized so that four forms may be placed on the third bed I, a web two forms wide may be used, as shown in Fig. 2, so that when associated with the two sections of web printed by the cylinders C and D, a twelve-page product will be produced, or again, a web may be used of but one form wide, as indicated in Fig. 5, so that when the same is associated with the sections of the web w , a ten-page paper will be produced.

15 A convenient way to arrange the gearing is to so design the same that the parts for manipulating the supplemental web w^1 may be thrown out of operation when the third cylinder is not used. One convenient way in which this may be done is shown in diagram in Fig. 6.

20 100 designates the driving shaft by which power may be applied to the machine. This shaft carries a pinion 101 which may mesh with a large gear 102 which gear is mounted on a shaft 103, which shaft carries a bevel pinion 104 which meshes with the large horizontal gear f^2 . Arranged on the outer end of 25 the shaft 103 is a pinion which, by means of intermediate 105, drives a large gear 106 secured upon a part I term the cam-shaft 107, which shaft may carry cams 108.

30 The looper L is arranged in bell-crank arms projecting from a shaft, and the looper L^1 is also arranged in bell-crank arms mounted upon a shaft, and the two sets of bell-crank levers may be connected together by means of suitable links l . The bell-crank 35 levers in which the looper L^1 is mounted may have suitable rollers which bear on the cams 108, and suitable springs may be provided to keep the same in constant and accurate engagement. By this means, the loopers 40 can be properly actuated.

45 By means of gears 109, 110 and 111, and a pair of miter gears, power can be transmitted to a shaft 112, the gear 111 being arranged preferably on the shaft of the feeding-out drum 19. By means of miter-gears 113 and 50 upright shaft 114, and miter-gears 115, the feeding-in device 12 may be driven. By means of miter-gears 116, the feeding-out drum 37 may be also driven. By means of 55 miter-gears 120, suitable gears 121, 122 123 and 124, the feeding-in device for the supplemental width web may be driven, the last gear 124 turning cams 125.

60 The looper L^2 may be arranged in bell-crank levers, which are mounted on a shaft, and may carry rollers bearing on the cams 125, suitable springs being also provided, if desired, to keep the rollers in constant engagement with the cams.

65 The miter-gears 116 and 120 are arranged

upon a shaft 119, which is mounted in line with the parallel shaft 112, and a suitable clutch 117—118 is arranged between the two shafts 112 and 119, so that the gearing for actuating the web-manipulating mechanism 70 for the supplemental web w^1 may be thrown into or out of operation, as the cylinder J is or is not used.

Any other desired form of gearing may be used, as desired, that indicated being merely 75 illustrated to show how the principle of my invention may be carried out.

Where I have used the term "form" herein, as applying to the width of a web, it is of course to be understood that the web is of a 80 width sufficient to give as a product a page printed from the form with the usual margins.

Other relative arrangements of beds may be used without departing from the scope of 85 my invention, as expressed in the claims, and the invention may be applied to machines capacitated to print a different number of pages than hereinbefore referred to.

Having thus fully described my invention, 90 what I claim and desire to secure by Letters-Patent is:—

1. The combination in a web printing press of three stationary form beds, a traveling impression cylinder coacting with each 95 bed, web-guides for leading a web so that the same will be perfected, a web-manipulating mechanism for said web, a deflector and web guides arranged so that a narrow width web may be perfected, a manipulating mechanism 100 for this web, and means for associating the products.

2. The combination in a web printing press of three stationary form beds adapted to hold four forms abreast, a traveling impression cylinder coacting with each bed, 105 web-guides for leading a web so that the same will be perfected, a manipulating mechanism for this web, a deflector and web guides arranged so that a web substantially one or 110 two forms wide may be perfected, a manipulating mechanism for this web, and means for associating the products.

3. The combination in a web printing press of three stationary form beds, a traveling impression cylinder coacting with each 115 bed, web guides for leading a web so that the same will be perfected by two of said impression cylinders, a web manipulating mechanism for said web, a slitter arranged to 120 slit said web into two sections, and an associator for associating said sections, a deflector and web-guides arranged so that a narrow width web may be perfected by the third impression cylinder, a manipulating 125 mechanism for this web, and means for associating this narrow width web with the two sections formed from the main web.

4. A printing press comprising three printing couples arranged in parallel planes, each 130

- couple consisting of a bed and co-acting cylinder, and means for feeding webs through said couples, to be perfected thereby.
5. A printing press comprising three stationary type beds arranged in parallel planes, and three reciprocating cylinders co-acting with the beds; with means for feeding webs through the press so that they shall be perfected thereby at each operation of the press.
10. 6. The combination in a web printing press of two stationary, horizontal form beds arranged in different planes and one in advance of the other, a third bed arranged in substantially the same horizontal plane as the uppermost of said two beds, a traveling impression cylinder coacting with each of said beds, suitable web-guides, a deflector, and web-manipulating mechanisms.
15. 7. The combination in a web printing press of three stationary form beds, a traveling impression cylinder coacting with each of said form beds, a single reciprocating mechanism for actuating all of said cylinders, web guides, a deflector, and web-manipulating mechanisms.
20. 8. The combination in a web printing press of three stationary form beds, a traveling impression cylinder coacting with each bed, a reciprocating mechanism for actuating said impression cylinders, connections whereby one of said impression cylinders may be thrown out of operation and the other two kept in operation, web guides and web manipulating mechanisms.
25. 9. The combination in a web printing press of three stationary form beds, a pair of carriers in which two impression cylinders are journaled, a reciprocating mechanism for said carriers, a second set of carriers in which a third impression cylinder is journaled, means for connecting and disconnecting the two sets of carriers, and suitable web guides and manipulating mechanisms.
30. 10. The combination in a web printing press of three stationary form beds, a traveling impression cylinder coacting with each form bed, connections whereby one impression cylinder may be thrown out of operation and the other impression cylinders left in operation, suitable web guides, a web manipulating mechanism, a second web manipulating mechanism arranged to manipulate a narrow width web, gearing for driving the two web manipulating mechanisms, and connections whereby this last web manipulating mechanism can be thrown into or out of operation as the third impression cylinder is or is not used.
35. 11. The combination in a web printing press of the stationary form bed, a traveling impression cylinder coacting therewith, suitable web guides, and a deflector arranged so that a web can be perfected, means for feeding the web continuously in and out, and a single looper around which the web is looped in opposite directions before it passes to and after it passes from said impression cylinder.
40. 12. The combination in a web printing press of a stationary form bed, a traveling impression cylinder coacting therewith, a feeding-in and a feeding-out device for the web, suitable web guides and a deflector, a single looper as 30, the whole so arranged that the web can be looped in opposite directions around said looper before it passes to and after it passes from said impression cylinder.
45. 13. The combination in a web printing press, of three stationary form beds, a traveling impression cylinder coacting with each form bed, suitable web guides and manipulating mechanism arranged so that a double width web can be perfected by two of said impression cylinders, suitable guides, and a second web manipulating mechanism arranged so that a narrow width web can be perfected by the third of said impression cylinders, a slitter for slitting the main web into two sections, an associator for associating said sections, web guides for leading the narrow width web so that the same will be associated inside of the main web, and a suitable folding device.
50. 14. The combination in a web printing press of three stationary form beds, a traveling impression cylinder coacting with each of said form-beds, suitable guides, and a web-manipulating mechanism arranged so that a full width or main web can be perfected by two of said impression cylinders, a slitter and associator for cutting the main web into two sections and associating the two sections, suitable web guides, a web-manipulating device, and a deflector arranged under the associating mechanism so that a narrow width web can be perfected by the third impression cylinder, and suitable guides adapted to associate the narrow width web with the two sections of the main web.
55. 15. The combination in a web printing press of three stationary form beds, a traveling impression cylinder coacting with each bed, web-guides for leading a web around two of the impression cylinders, so that the same will be perfected, a web manipulating mechanism for said web, a deflector, and web-guides arranged so that a narrow width web may be twice led around the third impression cylinder in opposite directions, a manipulating mechanism for this web, and means for associating the products.
60. 16. The combination in a web printing press of three stationary form beds, a traveling impression cylinder coacting with each bed, web-guides for leading a main web around two of said impression cylinders so that the same will be perfected thereby, a web manipulating mechanism for said web, a slitter arranged to slit said web into two sections, an associator for associating said sec-

tions, a deflector and, web-guides arranged to direct a narrow width web twice around the third impression cylinder and in opposite directions, a manipulating mechanism for this web, and means for associating this narrow width web with the two sections formed from the main web.

In testimony whereof I have hereunto set my hand, in the presence of two subscribing witnesses.
